UNITED STATES PATENT OFFICE

118,266

DESIGN FOR A WOVEN TEXTILE FABRIC

Andrew W. Roth, Harrison, N. Y., assignor to Roth-Getzoff & Company, New York, N. Y., a corporation of New York

Application August 25, 1939, Serial No. 86,876

Term of patent 3½ years

To all whom it may concern:

Be it known that I, Andrew W. Roth, a citizen of the United States, residing in Harrison, county of Westchester, State of New York, have invented a new, original, and ornamental Design for a Woven Textile Fabric, of which the following is a specification, reference being had to the accompanying drawing forming part thereof.

The figure is a plan view of a woven textile fabric showing my new design.

A unit of the design is enclosed between the dot and dash lines and is repeated in regular succession, as indicated by the extensions beyond the unit boundaries.

I claim:

The ornamental design for a woven textile fabric as shown and described.

ANDREW W. ROTH.
